Primary Examiner — Karen S Acker*Assistant Examiner* — Amy Wierenga*(74) Attorney, Agent, or Firm* — Clark & Brody**CLAIM**

The ornamental design for a studded molded mat, as shown and described.

DESCRIPTION

FIG. 1 is a top side perspective view of a studded molded mat showing our new design;

FIG. 2 is a front side view thereof;

FIG. 3 is a rear side view thereof;

FIG. 4 is a right side thereof;

FIG. 5 is a left side thereof;

FIG. 6 is a top view thereof; and,

FIG. 7 is a bottom side view thereof.

The broken lines in the drawing depict environmental subject matter that forms no part of the claimed design.
